CIRCUMFERENTIALLY ARRANGED COMBUSTION CHAMBER WITH ARCUATE WALLS DEFINING AN AIR FLOW PATH BETWEEN CHAMBERS

Robert M. Williams, Toledo, Ohio, and George F. Wislicenus, Baltimore, Md., assignors to Packard Motor Car Company, Detroit, Mich., a corporation of Michigan

Application October 8, 1948, Serial No. 53,438

12 Claims. (Cl. 60—39.65)

1

The invention relates generally to gas turbine units and more particularly to the structure of the combustion chamber portion of the unit and the relation of such portion to other portions of the unit.

In a gas turbine unit of the type herein contemplated, an air compressor or impeller may be employed to force air into the unit. Heat is then added to the air stream and a portion of the energy in the stream is utilized to operate a turbine to drive the compressor. The air stream issuing from the impeller has a relatively high velocity, which renders it difficult, if not impossible, to maintain combustion therein. A diffuser portion or section is therefore frequently included in the structure of the unit, where the velocity of the air is reduced sufficiently to maintain combustion in the adjoining combustion chamber portion. The necessity of utilizing a diffuser entails some disadvantages. Thus, it not only requires space in the structure of the unit, but it also involves some loss of efficiency. The impeller of the compressor may have an efficiency on the order of 90% or higher, while the diffuser may have a substantially lower efficiency, say, on the order of 70%.

The general object of the invention is therefore to provide a novel gas turbine in which the major portion of the air stream may flow at an aerodynamically optimum velocity without restriction due to requirements of combustion.

Another important object is to provide a novel gas turbine in which only a minor portion of the air stream need be subjected to substantial retardation to provide for combustion.

A further important object is to provide a novel gas turbine in which combustion and diffusion may be said to overlap, or in other words, a gas turbine in which both combustion and retardation of the flow may occur in one portion of the path of air stream in the unit.

Still another object is to provide a novel gas turbine in which the combustion chamber structure as well as the combustion gas emerging therefrom are completely surrounded or encased by the air stream so that adjacent structure of the unit is prevented from being overheated.

A still further object is to provide a gas turbine in which mixing of the air stream and the relatively hotter combustion gas is effected in a novel manner so that the resultant power stream is of substantially uniform temperature throughout.

Another object is to provide a novel gas turbine having an air passage through which air is delivered by the impeller and in which are vanes

2

controlling the flow of the air therein, and a combustion portion forming a continuation of such passage and provided with combustion chamber walls constituting in effect a continuation of said vanes.

Other objects and advantages will become apparent from the following description taken in connection with the accompanying drawings, in which:

10 Figure 1 is a side elevational view, with a portion thereof broken away, of a gas turbine embodying the features of the invention.

Fig. 2 is a view, on a larger scale, of the broken-away portion shown in Fig. 1.

15 Fig. 3 is a fragmentary perspective view of the portion of the structure shown in Fig. 2.

Fig. 4 is a fragmentary sectional view taken on the line 4—4 of Fig. 2.

Fig. 5 is a fragmentary sectional view taken 20 substantially on the line 5—5 of Fig. 2.

Fig. 6 is a fragmentary sectional view taken on the line 6—6 of Fig. 2.

Fig. 7 is a fragmentary sectional view taken on the line 7—7 of Fig. 8.

25 Fig. 8 is a view similar to Fig. 4 but showing a modified form of structure.

As heretofore mentioned, the present invention relates particularly to the structure of the combustion chamber section of the unit and its relation to the air compressor section. In the type of gas turbine herein contemplated, air is drawn inwardly through an air intake opening at the front of the unit, by means of a rotatively driven air impeller. The air discharged by the impeller

30 has a helical movement, and for this reason the delivery end of the air passage in the air compressor section, known as a collector, is provided with helically arranged guide vanes.

In gas turbines of this type, a diffuser is frequently employed immediately downstream from the air compressor section to receive the air stream from such compressor section and to diffuse or lower the velocity of the air. From the diffuser, the air stream flows into the combustion

35 chamber section, where heat energy is added to the air stream by the combustion of fuel. The reduction of velocity of the air stream in the diffuser is sufficient to permit combustion to be maintained in the combustion chamber section.

40 In the present construction, the diffuser and combustion chamber section are united or overlapped, and the air stream therein is handled in such a manner that the major portion thereof flows at an aerodynamically optimum velocity

45 without restriction because of combustion. Thus,

very little retardation on the major portion of the air stream may be required, while only a minor portion of the air stream is subjected to any substantial degree of retardation, and the combustion takes place in such minor portion. With this arrangement, the major portion, in which very little retardation has occurred, readily mixes with the combustion gases emerging from the combustion chamber. This result is accomplished by positioning a plurality of combustion chamber members in the path of the air stream as it leaves the collector or the delivery end of the compressor section, with the combustion chamber members spaced from one another so that the major portion of the air stream may flow therebetween. Such air as is needed in the combustion chamber members to support combustion therein is withdrawn from the air stream passing between the members and is permitted to enter the combustion chamber members for combustion of the fuel with a velocity therein suitable for such combustion.

The combustion chamber members cooperate with the guide vanes in the delivery end of the compressor section, and are shaped to control the direction of flow of the air stream. Thus, in the illustrative embodiment shown in the drawings, the members are shaped to reduce the helical character of movement of the air stream so that the stream thereupon flows substantially only in an axial direction. Because of this function, they are non-symmetrical in form. The combustion chamber members are supported in such a manner that the air stream flows not only between the respective members, but also between them and the adjacent casing structure so that each member is completely encased by a flow of relatively cool air, thus reducing the heat transmitted to the adjacent casing structure and other parts of the unit. At the discharge end of the combustion chamber members, the emerging combustion gases are likewise encased by the air stream so that not only is the surrounding structure in that portion of the unit protected from overheating, but the mixing of the air stream with the combustion gases is greatly facilitated.

The gas turbine utilizing the features of the invention is shown in Fig. 1 as a jet propulsion unit. As illustrated, the unit comprises an intake nozzle 10 provided with an annular front opening or eye, through which the supply of air is drawn. Rearwardly from the intake nozzle 10 is the air compressor section, indicated generally at 11. In the present instance, such compressor section comprises a portion 12 in which the compressor itself is mounted, and a delivery portion or collector 13, where some diffusion or retardation may occur. Immediately to the rear of the collector 13 is a combined diffuser and combustion chamber section, indicated at 14, and downstream from the latter is a turbine section 15 and a discharge nozzle 17.

As shown in Fig. 2 of the drawings, the compressor section 11 includes a rotary impeller 20 provided with blades 21 for creating an air stream directed both radially and rearwardly into the delivery portion 13, the air stream having a helical movement. Provided in the collector 13 is a plurality of guide vanes 22, between which the air flows into the combined diffuser and combustion chamber section 14. The impeller 20, in the present instance, is carried on a tubular shaft 23 driven by the turbine in the turbine section 15. It will be noted that the air stream delivered through the delivery portion 13 emerges there-

from in a generally rearward direction with a slight inward component, the air, however, maintaining its helical movement as heretofore mentioned.

5 The combined diffuser and combustion chamber section 14 comprises an annular inner casing 24 and an annular outer casing 25 enclosed by an outer shell 26. The casings 24 and 25 are in spaced relation to each other to provide an annular passage 25' to receive the air flow. As clearly shown in Fig. 2 of the drawings, both casings are of a conical shape with their smaller ends facing in a downstream direction, but the inner casing member 24 slopes inwardly at a steeper degree than the outer casing member 25, so that the passage therebetween, while decreasing in diameter, increases in its radial width.

The upstream end of the annular passage 25' between the casings 24 and 25 is where combustion takes place, while the downstream end of such annular passage is utilized for mixing of the combustion gases with the major portion of the air stream, the quantity of air delivered by the compressor being much greater than is necessary to support the combustion. Because of the quantity of air that is forced through the unit by the impeller, its velocity is so great that combustion must be protected from the flow so that such combustion may be maintained. To this end, a plurality of hollow combustion chamber members, indicated generally at 27, are mounted in the annular passage 25' between the casings 24 and 25 adjacent the upstream end thereof, with said members positioned in circumferentially spaced relation to each other so that the major portion of the air stream may pass therebetween. Such combustion chamber members are provided with an opening so that a minor portion of the air passing therebetween is withdrawn into the members to support combustion therein at a reduced average velocity.

Generally described, each combustion chamber member 27 has a pair of side walls 30 and 31, which are positioned to provide an aerodynamically optimum relation to the guide vanes 22 in the delivery end of the compressor section 11, the upstream ends of the combustion chamber members being aligned with the direction of flow of the air stream as it emerges from the compressor section 11. Such side walls, in the present instance, are shown as curved to straighten out the flow of the air stream, that is, to substantially eliminate its peripheral component and to direct it substantially in an axial direction. Thus, the side wall 30 is shown as being externally convex, while the external surface of the side wall 31 is concave. The side walls 30 and 31 are also divergent relative to each other in a downstream direction so as to provide increasing cross-sectional area within each combustion chamber member to permit proper flow of the combustion gases. With this relative arrangement of the side walls, each space between the combustion chamber members has an aerodynamically optimum cross-sectional area distribution throughout its length, the shape, however, changing because of the increasing divergence of the side walls relative to each other and because of the increasing radial width of the annular passage 25' formed by the casings 24 and 25. The cross-sectional area of the chamber members 27 are, of course, correlated to the cross-sectional areas of the passageway in the collector 13 and the annular passage 25' formed by the casings 24 and 25. With such cross-sectional area distribution for the spaces

between the combustion chamber members, the major portion of the air stream is free to flow therethrough at an aerodynamically optimum velocity, thereby decreasing the amount of retardation necessary on the major portion of the air stream.

The side walls 30 and 31, at their upper ends, may be spaced from the downstream ends of the guide vanes 22 and may blend into each other in a rounded form, as indicated at 32 in Fig. 4. Thus, the air stream, as it passes beyond the ends of the guide vanes 22, is free to flow without turbulence on either side of each combustion chamber member.

Each combustion chamber member 27 also includes an inner wall 33 and an outer wall 34, these two walls being positioned so that they generally parallel the casings 24 and 25. The two walls 33 and 34, however, are spaced from the casings 24 and 25 to permit a portion of the air flow to pass between such walls and the casings, thereby providing an encasement or envelope of relatively cool air entirely surrounding each combustion chamber member to prevent dissipation of heat therefrom to the adjacent casings 24 and 25. In the present instance, each combustion chamber member 27 is supported in such position by means of the small foot 35 formed at the downstream end of the juncture of the side wall 31 and the inner wall 33 and by a flange 36 extending throughout the length of the combustion chamber member at the juncture of the side wall 30 with the inner wall 33. The flange 36 and the foot 35 are rigidly secured to the inner casing 24. At the outer side of each combustion chamber member 27, there is a flange 37 (see Fig. 5) extending from the juncture of the side wall 30 and the outer wall 34 to provide the space between the outer wall 34 and the outer casing 25. The flange 37 and the radial portion of the flange 36 have the further function of directing the flow of air in their respective areas toward an axial direction. The inner and outer walls 33 and 34 are generally arcuate in form since they substantially parallel the casings 24 and 25. The side walls 30 and 31 occupy a substantially radial position, so that the cross-sectional shape of each combustion chamber member, particularly at the downstream end, may be said to be segmental.

Fuel for combustion within each combustion chamber member 27 may be supplied by a nozzle 49 mounted externally on the outer shell 26 and projecting inwardly through the outer casing 25 and through an aperture 48 in the outer wall 34 of the combustion chamber member. The air for combustion, as heretofore mentioned, is withdrawn from the flow of air in passage 25' which surrounds the respective combustion chamber members. To admit the air to the interior of each combustion chamber member, the concave side wall 31 may be provided with a plurality of perforations 42 (see Fig. 3), permitting the air to flow laterally from the main direction of the air stream into the combustion chamber. By utilizing a plurality of small perforations 42 and by withdrawing the air laterally, the velocity of the air flowing into the combustion chamber member is reduced sufficiently so that no difficulties are encountered within the combustion chamber of maintaining combustion therein. The diverging or flaring shape of each combustion member provides for the increase in volume of the combustion gases as combustion takes place, and such gases are permitted to flow outwardly in a relatively smooth stream through the open 75

downstream end of each combustion chamber member. Since the air stream encases each combustion chamber member, it similarly encases the emerging combustion gases, thereby protecting the casings 24 and 25 from the heat of such combustion gases downstream from the chamber members, and furthermore greatly facilitating the mixing of the relatively cool air stream with the hotter gases.

To further facilitate the mixing of the main portion of the air stream passing between the respective combustion chamber members with the combustion gases to attain the desired temperature distribution with a minimum flow energy or momentum loss, each concave side wall 31 is provided with means to thoroughly intermingle the air and combustion gases. Thus, a plurality of grooves open to the air stream in passage 25' and adapted to introduce the air into the emerging combustion gases in a layered formation is provided in the structure shown in Figs. 1 to 6. As clearly shown in Figs. 3 and 5, each concave wall 31 is corrugated, as at 44, to provide grooves 45 into which the air from the main air stream enters. Such grooves extend from a point intermediate the ends of each concave wall 31 to the downstream end of such wall with a gradually increasing depth so that the air enters therein without turbulence and is introduced into the combustion gases in a series of spaced layers so that the two are thereby readily intermingled.

The fuel introduced in the respective combustion chamber members 27 by the fuel nozzles 49 is initially ignited by an electrical spark plug or the like (not shown). In order to avoid the necessity of providing a spark plug for each combustion chamber, means is provided, in the present instance, for effecting ignition from adjacent chambers. With such means, one ignition device would be sufficient for a series of combustion chambers. In the present instance, twelve combustion chambers 27 are provided and only two ignition devices are utilized, such ignition devices being at diametrically opposite points. The means for effecting the ignition of the fuel in one chamber from combustion occurring in an adjacent chamber, in the present instance, comprises transfer tubes 46 extending across the spaces between the chamber members and connecting the side walls of adjacent combustion chamber members to provide communication therebetween. Preferably, such transfer tubes are located adjacent the upstream end of the combustion chamber members and extend transversely across the space between the adjoining members. When ignition takes place in one of the members, the pressure therein rises and creates a flow through the transfer member 46 to the adjoining chamber member and ignition is thereupon established in such adjoining member. Once the fuel is ignited in a chamber member, combustion continues to take place therein so long as the fuel is supplied thereto. With this arrangement, ignition takes place quickly in the entire series of combustion members so that, for practical purposes, two ignition plugs have been found sufficient to effect ignition of the fuel in all of the chambers.

The transfer tubes 46 not only function during the ignition of the fuel as described above, but also provide some definite advantages during operation of the turbine. Thus, it has been found that a pressure difference exists within each combustion member adjacent the respective sides thereof at the upstream end where the transfer

tubes 46 open into the chamber members. Such pressure difference creates a flow of hot gases through the transfer tubes, thus providing a means for preheating the fuel as it is introduced into the chamber members. In operation, it has been found that there is a higher pressure within each chamber member adjacent the point where the transfer tube extends from the wall 30 than there is directly opposite such point where the other transfer tube opens through the side wall 31. Considering two adjacent chamber members, there will, therefore, exist a pressure difference on opposite ends of each of the transfer tubes creating a flow of hot gases therethrough, the gases being taken from the chamber member adjacent the side wall 30 and introduced into the next chamber member through the wall 31. Such pressure difference may exist because of the non-symmetrical shape of each chamber member or it may be due to the aspirating action of the air entering the perforations 42 about the adjacent end of the transfer tube. Such air entering through the perforations 42 would tend to reduce the pressure at the adjacent end of the transfer tube so that a flow therethrough would be created.

The transfer tubes 46, since they extend generally transversely across the spaces between the combustion chamber members 27, may further function as guide vanes to assist in controlling the direction of flow of the major portion of the air stream between the chamber members. They thus cooperate with the casings 24 and 25 to determine the radial component of the flow.

In Figs. 7 and 8, combustion chamber members of somewhat modified form are shown. Thus, each combustion chamber member shown in these two figures comprises an outer wall 58, an inner wall 51, and a pair of side walls 52 and 53. The inner and outer walls 50 and 51, as well as the side walls 52 and 53, are shaped similarly to the corresponding walls in the preceding form, the side walls 52 and 53 being similarly curved.

The principal difference between the two forms lies in the construction of the upstream end of each combustion member. Thus, as shown in Figs. 7 and 8, the upstream end of the concave side wall 52 extends beyond the combustion chamber proper and is secured to one of the collector vanes 22, as indicated at 54, so that it constitutes a continuation thereof. The wall 53 is also extended somewhat, as shown at 55, to provide for smooth flow of the air stream. The extended portions of the walls 52 and 53 may be connected by wall portions 56 extending from the inner and outer walls 50 and 51 to provide a relatively dead space in which the fuel supply means may be mounted. The chamber proper is separated from such space by a transverse wall 57 so that the interior of the chamber is completely enclosed by wall structure at its upstream end.

Due to the direction of flow of the air stream, the concave walls 52, as is the case with the walls 31 in the other form, are at the high pressure side of the air stream and may be called the high-pressure walls. The walls 53 in the form shown in Figs. 7 and 8, as well as the walls 30 in the form shown in the previous figures, may be said to constitute the low-pressure side of the space between the adjacent members. Since the walls 52, as well as the walls 31 in the other form, are at the high-pressure side of the stream, the perforations provided to admit air to the interior of the combustion chamber are placed in such walls. In the form of combustion chamber shown in Figs. 7 and 8, a larger number of perforations,

indicated at 60, are provided than in the previous form. In the form of Figs. 7 and 8, the perforations are located in an area extending from a point intermediate the ends of the chamber substantially to the extreme upstream end of the chamber proper, as is evident in Fig. 7. The perforations 60 thus extend entirely about the adjacent transfer tube 46. These perforations thus will admit primary air to support combustion within each chamber member. Additional primary air may be admitted through the upstream end of each combustion chamber by means of perforations 61 in the outer wall 58 and extending adjacent the low-pressure wall 53. Secondary air may be admitted to the interior of each chamber through larger perforations 62 provided in the downstream portion of each side wall 52. The quantity of air admitted through the perforations 62 may be more than sufficient to insure complete combustion, so that the perforations 62 also function as a means for intermingling some of the air flow passing through the spaces between the respective chamber members with the combustion gases. Further mixing of the major portion of the air stream passing through such spaces with the combustion gases emerging from the chamber members can be accomplished by cutting back the downstream edges of the side walls 52 and 53 and the inner wall 51, as indicated at 63.

With the combined diffuser and combustion chamber section disclosed herein, the major portion of the air stream is permitted to flow in passage 25' between the respective combustion chamber members and between them and the casings 24 and 25. Thus, such major portion of the air stream may be maintained at an aerodynamically optimum velocity and need not be retarded to the extent that has heretofore been deemed necessary. While some reduction in the velocity of major portion may be found desirable, such retardation is not required because of the combustion within the combustion chamber members. However, the air withdrawn from the main air stream through the apertures 42 is so retarded that its velocity does not interfere with proper combustion within the chamber members. By virtue of the fact that the major portion of the air passes outside of the combustion chamber members, the heat thereof is not dissipated to the casings 24 and 25 so that no overheating thereof occurs. Such encasement effected by the air stream also facilitates the mixing of the relatively cool air with the combustion gases emerging from the chamber members. Further mixing is effected by the layered formation in the air stream produced by the grooves 45 in the downstream end of each chamber member. A power stream is thus generated in which the air and combustion gases are thoroughly mixed and uniform temperature therein is attained before passing to the turbine section 45.

We claim:

1. A gas turbine comprising an air compressor section having guide vanes positioned generally radially in the delivery end thereof, and a combined diffuser and combustion chamber section having an annular air passage for receiving the air stream from the delivery end of said air compressor section, and a plurality of hollow combustion chamber members mounted in said air passage in circumferentially spaced relation to each other to permit flow of the air stream therebetween and having perforations to admit a portion of the air stream into said members to

support combustion therein, said members having radial walls that are fixed integrally with and form continuations of said vanes with the spaces between said walls of the respective members such as to maintain the flow at an aerodynamically optimum velocity.

2. A gas turbine comprising an air compressor section having an annular delivery passage provided with radially extending helical guide vanes, and a combined diffuser and combustion chamber section having an annular passage connected to said delivery passage for receiving the air stream from said delivery passage, and a plurality of hollow combustion chamber members located in said air passage in circumferentially spaced relation to each other to permit flow of the air stream therebetween and having perforations to admit a portion of the air stream into said members to support combustion therein, said members having arcuate inner and outer walls connected by radially extending walls, the latter having an integral connection with each of said vanes respectively and constituting continuations of said vanes, said continuations being shaped to effect a change from a helical form into an axially extending form to change the air flow from helical to axial.

3. A gas turbine comprising an air compressor section having an annular delivery passage provided with radially extending helical guide vanes, and a combined diffuser and combustion chamber section having an annular air passage connected to said delivery passage for receiving the air stream from said delivery passage, and a plurality of hollow combustion chamber members located in said air passage in circumferentially spaced relation to each other to permit flow of the air stream therebetween and having perforations to admit a portion of the air stream into said members to support combustion therein, said members having arcuate inner and outer walls connected by radially extending walls, the latter having an integral connection with each of said vanes respectively and constituting continuations of said vanes, the radially extending walls of each member diverging from each other in a downstream direction to provide a flaring combustion chamber and progressively changing into axially extending form to change the air flow from helical to axial.

4. A gas turbine comprising an air compressor section, and a combustion chamber section comprising a pair of radially spaced annular casings providing an annular passage therebetween for receiving the air stream from the compressor section, said casings diverging relative to each other in a downstream direction and a plurality of hollow combustion chamber members situated in said passage and being disposed in circumferentially spaced relation to each other to permit flow of the air stream therebetween, each member having arcuate inner and outer walls paralleling said casings and radially extending walls diverging from each other in a downstream direction to provide a flaring combustion chamber, each space between the members themselves and the annular casings having an aerodynamically optimum distribution of cross-sectional area throughout its length to maintain the air therethrough at an aerodynamically optimum velocity.

5. A gas turbine comprising an air compressor section for delivering a helically moving air stream, and a combustion chamber section having an annular passage to receive the air stream, and a plurality of combustion chamber members

located in said passage in circumferentially spaced relation to provide spaces for the air stream to pass therebetween, each of said members comprising a pair of inner and outer walls connected by a pair of walls extending substantially radially and extending downstream and being respectively concave and convex, the concave wall having apertures adjacent its upstream end for admitting air from the air stream into said member to support combustion therein at a reduced average velocity.

6. A gas turbine comprising an air compressor section, and a combustion chamber section having an annular passage for receiving the air stream from the compressor section, and a plurality of hollow combustion chamber members having radially disposed side walls, said members being mounted in said passage in circumferentially spaced relation to each other to provide radially positioned spaces for the air stream to pass between the members, said members being perforated to admit air from the air stream to support combustion therein and having their downstream ends open for discharge of the combustion gases into the air stream, each of said members having a plurality of grooves on one of said radially disposed sides thereof, said grooves extending longitudinally and opening from the radially positioned spaces between said grooved sides and their adjacent members for introducing the air in a layered formation into the combustion gases to facilitate mixing thereof.

7. A gas turbine comprising an air compressor section for delivering a helically moving air stream, and a combustion chamber section having an annular passage to receive the air stream, and a plurality of combustion chamber members located in said passage in a circumferentially spaced relation to provide spaces for the air stream to pass therebetween, each of said members comprising a pair of inner and outer walls connected by a pair of walls extending substantially radially and being respectively concave and convex, the concave wall being corrugated inwardly adjacent its downstream end whereby air from the air stream is introduced in a layered formation into the combustion gases emerging from the member to facilitate mixing thereof.

8. A gas turbine comprising an air compressor section for delivering a helically moving air stream, and a combustion chamber section having an annular passage to receive the air stream, and a plurality of combustion chamber members located in said passage in circumferentially spaced relation to provide spaces for the air stream to pass therebetween, each of said members comprising a pair of inner and outer walls connected by a pair of walls extending substantially radially and being respectively concave and convex, the concave wall having apertures adjacent its upstream end for admitting air from the air stream into said member to support combustion therein at a reduced average velocity and being bent inwardly of the member adjacent its downstream end along a plurality of longitudinal lines to form a plurality of grooves increasing in depth in a downstream direction whereby air from the air stream is introduced in a layered formation into the combustion gases emerging from the member to facilitate mixing thereof.

9. A gas turbine comprising an air compressor section for delivering a helically moving air stream and a combustion chamber section comprising a pair of radially spaced annular casings providing an annular passage therebetween

11

to receive the air stream, and a plurality of hollow combustion chamber members mounted in said passage in spaced relation to each other to permit the air stream to pass therebetween, each member comprising a pair of arcuate walls substantially paralleling said casings, a pair of substantially radial walls extending generally longitudinally of the passage but diverging from each other in a downstream direction, said radial walls being curved to straighten the direction of air flow and with said arcuate walls giving the chamber member a segmental cross-sectional shape, and flanges projecting from edge portions of the member into engagement with said casings to support the member in spaced relation to said casings.

10. A gas turbine comprising an air compressor section, and a combustion chamber section having a passage for receiving the air stream from said air compressor section, and a plurality of hollow chamber members mounted in said passage in spaced relation to each other to permit a major portion of the air stream to pass therebetween, and guide vanes positioned between the chamber members and extending from one chamber member to another to guide the flow of said major portion of the air stream, said guide vanes being hollow and providing communication between said chamber members to conduct hot gases from one member to another.

11. A gas turbine comprising an air compressor section having guide vanes in the delivery end thereof, and a combustion chamber section having an annular passage for receiving the air stream from said delivery end, and a plurality of hollow chamber members mounted in said passage in circumferentially spaced relation to each other and perforated to admit a portion of the air stream into said members with the remaining portion of the air stream flowing therebetween, each of said members having a pair of side walls for guiding the flow of said remaining

12

portion with one of said side walls secured at its upstream end to one of said vanes.

5 12. A gas turbine comprising an air compressor section for delivering a helically moving air stream and having helical guide vanes in its delivery end, and a combustion chamber section having an annular passage for receiving said air stream, and a plurality of hollow chamber members mounted in said passage in circumferentially spaced relation to each other and perforated to admit a portion of the air stream into said members with the remaining portion of its air stream flowing therebetween, each of said members having a pair of side walls curved to control the direction of flow of said remaining portion, one of said side walls defining the high pressure side of said flow and the other side wall defining the low pressure side, the high pressure side wall having its upstream end secured to and forming 15 a continuation of one of said vanes.
